UNITED STATES PATENT OFFICE

ROBERT LEFFEL, OF LOUISVILLE, KENTUCKY, ASSIGNOR TO STANDARD SANITARY MANUFACTURING COMPANY, A CORPORATION OF NEW JERSEY

DRINKING FOUNTAIN

Application filed March 18, 1927. Serial No. 176,401.

This invention relates to drinking fountains and more particularly to those of the bubbler type wherein a column or stream of water issues through a suitable jet opening in such a way as to permit drinking directly from the stream.

In fountains of this type any variation in the pressure of the water in the supply line causes a consequent variation in the shape, height or other characteristic of the fountain stream, and these variations are frequently such as to render it difficult to drink from the stream with any degree of success or satisfaction.

An object of this invention is to provide a drinking fountain of the type set forth of such construction and arrangement as to prevent variations from the normal in the pressure of the water supply from affecting the fountain flow.

A further object is to provide a water regulator for use with a supply line of such construction and arrangement that the flow passing said regulator and issuing from the water jet opening will be maintained substantially constant irrespective of pressure variations in the associated line.

In those drinking fountains where the ordinary round or cylindrical stream is projected into the air for drinking purposes a large number of bubbles or drops break off from the stream and are an annoyance to the drinker and cause a continual splashing.

A further object of this invention is to provide an arrangement for projecting a stream of drinking water of such character as to eliminate these objectionable features.

A further object is to provide a device of the type set forth which will be simple and rugged in construction, positive and reliable in operation and relatively cheap to manufacture and assemble.

These and other objects which will be apparent to those skilled in this particular art are accomplished by means of the invention illustrated in the accompanying drawings, in which Figure 1 is a transverse sectional view through a drinking fountain constructed in accordance with one form of this invention. Fig. 2 is a plan view of the bubbler or foun-

tain head, and Fig. 3 is a view similar to Fig. 1, showing certain details on an enlarged scale.

The particular arrangement which has been chosen for the purposes of illustration consists of a so called "slant stream" drinking fountain, wherein the bubbler or fountain head is so formed as to project a stream of drinking water in an arcuate path. Water is supplied to the bubbler from a suitable inlet which may have a hand controlled valve for permitting or shutting off the flow of water, and the usual drain outlet is provided for draining the fountain bowl. A water regulator is associated with the inlet or supply pipe and is of such form as to maintain a substantially constant flow through the bubbler or fountain head irrespective of variations in the water supply pressure. The regulator provides an opening of variable size through which the supply water flows to the bubbler and the regulator is so formed that it is responsive to variations in the supply pressure so as to vary the size of this opening and to reduce its area, and consequently the flow therethrough upon an increase in pressure in the supply line, and to increase the size of the opening upon a decrease in pressure in the supply line, thus maintaining a substantially constant stream flow in the fountain irrespective of variations in the pressure in the supply line. A by-pass connects the supply line with the drain pipe below the fountain bowl so that any excess of water which the regulator prevents passing to the bubbler head is by-passed to the drain pipe and the regulator is so formed that the by-pass opening will be opened automatically to an extent proportional to the excess of pressure in the inlet line.

As illustrated, the present invention is shown applied to a fountain bowl 1 of usual construction having a drain outlet 2 communicating with an ordinary drain pipe 3. A water supply line 4 is connected to the fountain inlet pipe 5 through a spring controlled, manually operable valve 6 which normally shuts off the supply of water but which can be operated by the handle 7 to permit

water to flow from the supply line to the inlet pipe 5, as is well understood in this art. The inlet pipe 5 extends upwardly through the fountain bowl at one side thereof and has a fountain head or bubbler 8 secured to the top thereof by a suitable coupling 9. The bubbler is provided with a jet opening 10 positioned so as to form a "slant stream" of water which is thrown in an upwardly extending arc as is well known.

10 A stream regulator nut 11 having a circular series of holes 12 forming water passages is secured in the upper end of the inlet pipe 5 within the fountain head for the purpose of 15 distributing the flow of water into the bubbler so as to completely fill all parts of the latter and to prevent a greater flow at one side thereof than at another.

20 A regulator is associated with the inlet pipe for maintaining a substantially constant flow through the jet opening 10. As illustrated, this regulator includes a regulator plug 13 which may be conveniently mounted in the stream regulator nut 11 and which extends downwardly therefrom. The lower portion 14 of the plug is reduced in diameter and an annular groove 15 is formed at the top of this reduced portion. A control sleeve 16 is 25 slidably mounted within the inlet pipe below the plug and is spring pressed downwardly by a helical spring 17 into tight fitting engagement with a perforated disc 18 mounted on an annular ledge 19 just below a by-pass opening 20 which is connected to the drain 30 pipe 3 by the by-pass connection 21.

35 The regulator plug 13 is adapted to be so positioned that an annular orifice of variable size is formed between the groove 15 of the plug and the upper end of the bore formed 40 in the control sleeve 16.

45 The disc 18 upon which the control sleeve normally seats is provided with a circular series of openings 22 for causing the water flowing through the inlet pipe 5 to impinge against the lower pressure surface 23 at the bottom of the sleeve. The outer diameter of the sleeve at the bottom thereof is reduced so as to form a passage 24 communicating with the by-pass opening 20 so that water 50 can flow into the by-pass opening and through the by-pass connection as soon as the sleeve 16 is raised from engagement with the disc 18 against the pressure of the spring 17.

55 It will be apparent that the annular flow controlling opening formed between the plug 13 and the sleeve 16 can be adjusted so that a predetermined stream flow will emerge from the jet opening 10. If the valve 6 is open and the fountain in use, an increase in the water 60 pressure in the supply line instead of causing an undesirable spurt in the flow through the jet opening 10 will increase the water pressure against the surface 23 against the bottom of the sleeve and cause the latter to be 65 lifted vertically a distance dependent upon

the degree of increase in such water pressure. The annular flow orifice at the top of the sleeve will be decreased by this vertical movement in accordance with the increase in pressure so as to counteract the greater velocity of flow therethrough and thus maintain a constant flow through the jet opening.

70 The surplus water reaching the inlet pipe 5 as a result of increased pressure in the supply line will flow through the annular passage 24 to the by-pass opening 20 and through the by-pass connection 21 to the drain outlet. Upon a decrease in the supply pressure the sleeve 16 will be lowered so as to reduce or cut off the flow of water through the by-pass and at the same time the annular opening at the top of the sleeve will be increased in size to compensate for the reduction in the pressure of water in the supply line and thus maintain a constant flow through the jet orifice irrespective of such reduction.

75 In order to eliminate the objectionable splashing and breaking up of the ordinary stream into a number of small bubbles, the present invention provides a jet opening of such form that the breaking of the stream into spray or the splashing thereof is eliminated. This is accomplished by forming the jet opening 10 of an irregular or non-circular conformation. As illustrated, the jet opening has a circular portion 25 in the side of the fountain head or bubbler 8 and a slot 26 is formed on the upper side of the circular portion so as to provide a fountain stream having a smooth surface on the top thereof which effectively 80 prevents the breaking up of the stream.

85 Although I have described what I now consider to be the preferred embodiment of this invention it will be apparent that various changes, additions, substitutions and omissions can be made therein without departing from the spirit of the invention or the scope of the appended claims. What I claim as new and desire to secure by Letters Patent is:

90 1. A drinking fountain having in combination a water supply line, a fountain head communicating therewith, an orifice through which water in said supply line flows to said fountain head, a drain pipe spaced from said supply line, a by-pass connection between said supply line and said drain pipe and mechanism located wholly within said supply line for causing any surplus of water in said supply line to flow through said by-pass to said drain pipe so as to maintain a substantially constant flow through said orifice.

95 2. The combination in a plumbing fixture of a water supply line adapted to deliver water thereto, a flow opening in said supply line through which said water passes, a by-pass opening in said supply line on the pressure side of said flow opening and mechanism located wholly within said supply line between said openings for varying the effective 100

sizes of said openings so as to maintain a constant flow through said first opening.

3. The combination in a plumbing fixture of a water supply line adapted to deliver water thereto, a flow opening of variable size through which said water passes, a by-pass and mechanism located wholly within said supply line and subject to the pressure of water therein for opening said by-pass and restricting said flow opening when said pressure exceeds a predetermined amount.

4. The combination in a plumbing fixture of a water supply line adapted to deliver water thereto, a flow controlling opening of variable size through which said water passes, a by-pass opening and mechanism including a movable sleeve located wholly within said supply line and operatively associated with said openings and formed so as to be positioned in accordance with the water pressure in said supply line for varying the relative sizes of said openings to maintain a constant flow through said flow opening.

5. The combination in a plumbing fixture of a water supply line adapted to deliver water thereto, a sleeve slidably mounted within said supply line, a plug of varying cross section extending into one end of said sleeve so as to form an annular flow opening through which said water passes, a by-pass opening normally discommunicated from said supply line and means for changing the position of said sleeve in accordance with the pressure of water within said supply line so as to establish communication with and divert water from the supply line into the by-pass and to vary the relative sizes of said openings whereby a substantially constant flow through said flow opening is obtained under varying conditions of water pressure.

6. The combination in a plumbing fixture of a water supply line adapted to deliver water thereto through an opening interposed between the supply line and the fixture, mechanism responsive to the pressure in said supply line for decreasing the size of said opening upon an increase in pressure in said supply line and for increasing the size of said opening upon a decrease in said pressure, and a by-pass controlled by said mechanism for discharging surplus water from said line in response to the water pressure increasing to a predetermined value.

In testimony whereof, I have hereunto subscribed my name this 10th day of March, 1927.

ROBERT LEFFEL.
